SIRUP MIXING DEVICE

Raymond J. Unser, Faribault, Minn.

Application October 25, 1950, Serial No. 192,057

2 Claims. (Cl. 222—56)

1

This invention relates to liquid mixing apparatus and particularly to apparatus for intermixing predetermined volumes of two or more liquids.

Soft drink concentrated syrups are prepared with sufficient sugar content to prevent fermentation thereof. However, when this syrup is diluted before carbonating the drink, it will spoil in a relatively short time. Therefore, it is necessary to mix only small portions of the liquid to be carbonated to prevent wastage from spoiling of the diluted concentrate.

It is an object of my invention to provide apparatus constructed to mix predetermined volumes of two or more liquids by an automatically controlled mechanism.

It is another object to provide mechanism for mixing a batch of liquid produced by intermixing predetermined volumes of two or more liquids through a single cycle of operation.

More specifically, it is an object to provide two or more liquid supply tanks, each having a liquid delivering bucket, normally positioned therein and adapted to be shifted from filling position to dumping position to discharge liquid from the bucket into a single mixing compartment.

It is still another object to provide a number of liquid carrying buckets in the form of elongated troughs, each being closed at one end, and mounted on a single shaft to be swung upwardly from filling position to dumping position and thereafter returned to filling position, a single revolution power source being provided for actuation of a pitman to oscillate said bucket on the shaft and operate the mechanism through a single cycle of operation.

These and other objects and advantages will more fully appear from the following description made in connection with the accompanying drawings wherein like reference characters refer to the same or similar parts throughout the several views and in which:

Fig. 1 is a side elevational view of my mixing apparatus with a portion of the wall broken away and showing the mixing buckets in filling position by full lines and in dumping position by dotted lines.

Fig. 2 is a top plan view of the structure shown in Fig. 1.

Fig. 3 is a transverse vertical sectional view taken substantially along the line 3—3 of Fig. 2.

Fig. 4 is an elevational view showing the single revolution motor and the pitman actuated thereby;

Fig. 5 is a diagrammatic view of the electric

wiring circuit for the apparatus illustrated; and Fig. 6 is a fragmentary traverse sectional view taken substantially along the line 6—6 of Fig. 4.

As shown in the accompanying drawings, I provide a compartmented liquid confining tank 8 having, in the form shown, a pair of supply compartments 9 and 10 divided by a longitudinally disposed partition 11 terminating at a transversely disposed partition 12, which forms a mixing compartment 13. A transversely disposed pivot shaft 14 is mounted across the upper portion of the tank 8 and in the form shown, is disposed directly above the transverse partition 12. A pair of liquid carrying and delivering buckets 15 and 16 are journaled for oscillation in side by side relationship on said shaft 14. These buckets 15 and 16 are in the form shown, elongated troughs, which are closed at the free ends thereof, a partition 15a closing the end of the water supply trough 15 and a partition 16a having the adjustable level controlling notch 16b closing the end of syrup supply trough 16. The two troughs 15 and 16 are rigidly interconnected by an inverted U-shaped yoke 17, and are slightly spaced to straddle the longitudinal partition 11, the bucket 15 operating in water supply compartment or tank 9, and the bucket 16 operating in syrup supply compartment 10.

A source of actuating power, such as the single revolution electric motor 18 is provided, and in the form shown, is mounted on a suitable platform 19 fixed at one end of the tank 8. The motor 18 is wired in a conventional manner, so that whenever the switch 29 has been closed to start the motor, the same will continue to operate for a single revolution, and then will be automatically stopped. The details of this internal wiring of the motor 18 are not shown, but there are a number of such motors conventionally being produced for sale such as a model 604B6 motor made by Minneapolis Honeywell Company, Minneapolis, Minnesota, and shown generally in Patent No. 2,194,701. It should be noted that the motor disclosed in said patent must be modified to produce a 360° rotation instead of the 180° rotation produced by the circuit and limit switches illustrated in said patent. The rotary shaft of motor 18 is disposed transversely of the tank 8, and a crank arm 20 is fixed thereto. The crank arm 20 has an elongated slot 20a formed in the outer portion thereof, as best shown in Fig. 4. An adjustment pin 22 is inserted through said slot 20a, as best shown in Fig. 6. A bushing and collar unit 21 is journaled on said bushing to be reciprocated by crank arm 20

during the rotation thereof. A locking nut 22b is threadably mounted on the end portion of pin 22 for freely locking said pin in desired adjusted position in slot 20a. An adjustment is provided for varying the length of pivot arm 21, such as the two overlapping arm sections releasably secured together by a pair of bolts and nuts 24. The length of each reciprocating stroke of pitman arm 21 can be varied by shifting the pin 22 in slot 20a. This permits the length of arcuate 10 swinging movement of troughs 15 and 16 to be adjustably varied. By varying the length of pitman arm 21, the terminal positions of the two troughs may be easily set.

In the form shown, each compartment 9, 10, 15 and 13 has a float mounted therein. These floats respectively designated by the numerals 25, 26, and 27 are connected to cam actuated electric limit switches, which are closed when the liquid reaches a predetermined minimum level, and 20 which are opened when the liquid reaches a predetermined maximum level. The float 27 actuates the limit switch 29, as shown in Fig. 5, which controls the electric motor 18. When the level and liquid in mixing compartment 13 falls below the predetermined level, the switch 29 will be closed to start electric motor 18, which is designed in any conventional manner to operate through only one revolution. The two floats 25 and 26 respectively control the limit switches 30 30 and 31, which are respectively connected in series with a pair of solenoid valves 32 and 33, which control the flow of liquid from suitable sources of supply into the respective compartments 9 and 10. A pair of supply pipes, as shown in Fig. 2, and respectively designated by the numerals 34 and 35, are connected with any suitable source of liquid. In the form shown, the pipe 34 is connected with a source of water supply and the pipe 35 is connected with a source of syrup concentrate supply, and the solenoid valves 32 and 33 respectively control the flow of these liquids through the respective pipes 34 and 35. An outlet pipe 36 is connected into the bottom of the mixing compartment, and runs to a conventional carbonator unit (not shown).

Operation

The following is a description of the operation of my new and improved syrup mixing apparatus. When the liquid in the mixing tank falls below a predetermined level, the float 27 closes the limit switch 29 and starts the motor 18, which operates through exactly one revolution. When the motor revolves, the pitman arm will be reciprocated to oscillate the yoke 17 and to swing the buckets 15 and 16, which have their free ends normally disposed below the surface of the liquid in the respective tanks 9 and 10, into dumping position as shown by dotted lines in Fig. 1. Thus, it may be seen that a predetermined volume of water from tank 9 is mixed with a predetermined volume of syrup concentrate from tank 10 into mixing chamber 13. The level of the liquids in tanks 9 and 10 is maintained substantially constant by the floats 25 and 26 and the limit switches 30 and 31, and the pitman 21 and crank 20, to which said pitman is connected by pin 22 positions the troughs 15 and 16 in precisely the

same filling position during each cycle of operation. A volume of liquid retained by syrup mixing bucket 16 can be varied by swinging the closure of notch 16b in to open a portion of the level control notch 16b. Obviously, the level in tank 10 must be maintained somewhat higher than the level in tank 9 since the trough 16 is considerably shorter than the trough 15.

It will be seen that I have provided a relatively simple, yet highly efficient, machine for intermixing two or more liquids in precisely predetermined volumes, in which the mixing buckets combine with a dumping apparatus and liquid level maintaining apparatus to provide an automatically operated mechanism.

It should be kept in mind that any number of compartments may be provided with a similar number of troughs mounted on the same shaft to intermix any number of liquids.

Also, it should be kept in mind that the liquid supplied from supply pipe 36 could conceivably be connected to a supply compartment such as compartment 9 of a similar device, and have another liquid mixed thereto. In other words, two or more devices, as shown in applicant's disclosure, could be connected in series to successfully intermix more than two liquids.

It will, of course, be understood that various changes may be made in the form, details, arrangement, and proportions of the parts without departing from the scope of my invention.

What I claim is:

1. A liquid mixing device comprising a plurality of substantially parallel liquid supply tanks disposed in side by side relation, an intermixing tank extending transversely across one end of said supply tanks, an elongated shaft mounted transversely of the supply tanks, an elongated trough-like supply bucket mounted in each supply tank for swinging movement on the longitudinal axis of said transverse shaft, a yoke rigidly interconnecting said supply buckets, a pitman pivotally connected to said yoke, a source of single revolution rotary power connected to said pitman for actuating the same to swing said buckets from filling position to dumping position and back to filling position, the discharge ends of said buckets being disposed to simultaneously deliver the respective liquids into said mixing tank when in discharge position, and means for actuating said power source when the liquid in said mixing tank falls below a predetermined level.

2. The structure set forth in claim 1, and means for adjusting the length of said pitman to permit the terminal positions of the buckets to be varied, and means for adjusting the length of the pitman stroke to permit the swinging movement of the buckets to be varied.

RAYMOND J. UNSER.
